UNITED STATES PATENT OFFICE.

LANSING ONDERDONK, OF NEW YORK, N. Y.

DESIGN FOR A SEWING-MACHINE FRAME.

52,854.

Specification for Design.

Patented Jan. 7, 1919.

Application filed March 2, 1915. Serial No. 11,564. Term of patent 14 years.

To all whom it may concern:

Be it known that I, LANSING ONDERDONK, a citizen of the United States, residing at New York city, in the county of New York, State of New York, have invented a certain new and ornamental Design for a Sewing-Machine Frame, of which the following is a description, reference being had to the accompanying drawing and to the figures of reference marked thereon.

My invention relates to a new and ornamental design for sewing machine frames.

The figure represents a perspective view of a sewing machine frame embodying my new design.

I claim—

The ornamental design for a sewing machine frame, as shown.

In testimony whereof, I affix my signature in the presence of two witnesses.

LANSING ONDERDONK.

Witnesses:

W. E. BARNES,
C. H. COCKS.
